UNITED STATES PATENT OFFICE.

CHARLES FOSTER ASHLEY, OF BOLTON, NORTH CAROLINA.

SAWMILL-CARRIAGE FEED.

1,072,805.

Specification of Letters Patent. Patented Sept. 9, 1913.

Application filed April 25, 1913. Serial No. 763,555.

To all whom it may concern:

Be it known that I, CHARLES F. ASHLEY, a citizen of the United States, residing at Bolton, in the county of Columbus and State of North Carolina, have invented certain new and useful Improvements in Saw-mill-Carriage Feeds; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to saw mills, and more particularly to saw mill carriages; and it has for its object to provide an improved construction having relation to the feed or travel of the carriage, and to effecting an automatic control or check in the travel of the carriage in the event of the sawyer losing control or failing at the proper time to check or reverse the travel of the carriage.

To the accomplishment of the foregoing and such other objects as may hereinafter appear, the invention consists in the features hereinafter particularly described and then sought to be clearly defined by the claims, reference being had to the accompanying drawing forming a part hereof and in which—

Figure 1 is a side elevation of so much of a saw mill carriage and feed as necessary to illustrate my invention applied thereto; Fig. 2 is a top plan view of the parts illustrated in Fig. 1; Fig. 3 a perspective view of the parts embodying my invention, showing the relation of the several parts, with the carriage, its track and frame omitted.

In the drawing the numeral 1 designates a supporting frame of any appropriate construction; 2 a carriage; and 3 a fluid pressure cylinder having its piston 4 connected by a rod 5 to a swinging bracket 6 attached to the carriage, which parts may be of any approved type of construction.

Beneath the carriage, at opposite ends and below the cylinder 3, there is arranged a series of casings, those at one end designated by the characters 1^a, 2^a, 3^a, 4^a and 5^a, in communication with each other, and those at the other end by the characters 1^b, 2^b, 3^b, 4^b, and 5^b, in communication with each other. Each of the casings with the

exception of casings 1^a, and 1^b are provided with valves, and the casings 3^a, 4^a, 3^b, and 4^b are provided with exhaust pipes 6^a, 7^a, 6^b, 7^b, respectively, of which the two former 60 may discharge into a main exhaust pipe 8^a and the other two into a main exhaust pipe 8^b.

A live steam pipe 9^a leading from a suitable source of controllable supply opens 65 into the casing 4^a and from it a by-pass pipe 10^a leads to the casing 5^a and a branch pipe 11^a from the same casing to the casing 1^a from which a pipe 12^a leads into one end of the piston cylinder 3; while a live 70 steam pipe 9^b leading from the source of supply opens into the casing 4^b and from it a by-pass pipe 10^b leads to the casing 5^b and a branch pipe 11^b from the same casing to the casing 1^b from which a pipe 12^b leads 75 into the adjacent end of the piston cylinder 3. It will thus be observed that the construction of the casings and their connections are the same at both ends of the piston cylinder.

The casings 3^a 4^a 3^b 4^b are each provided with a valve of approved construction which in one position will cut off the supply of live steam and open to its exhaust pipe and in another position will open to 85 live steam and cut off its exhaust, while the valves of the casings 2^a and 2^b will be an approved construction which will in one position open communication between their casings and the adjoining casings at opposite sides thereof, there being no separate exhaust pipes provided for these particular casings; the same being true of the casings 5^a and 5^b and their valves which latter control the supply of live steam by way of 90 the by-passes.

The casings 3^a 3^b and their contained valves constitute the sawyer's valves and are controlled by him through the rod 7 which at one end is connected to the bell-crank lever 3^c connected to the stem of the valve in casing 3^a and intermediate of its ends to the bell-crank lever 3^d of the valve in casing 3^b and also to a bell-crank lever 8 fulcrumed on a crossbar 9 and provided 100 with an operating rod 10 for the sawyer. The bell-crank lever of the valves to casings 3^a and 3^b are formed as illustrated so that when the connecting rod is moved in one direction the valve in one casing will 105 be opened to live steam and in the other casing opened to exhaust, and vice versa.

when the rod is moved in the other direction.

A trip-lever crank shaft 11 is journaled in a suitable part of the frame near the limit 5 of travel of the carriage in one direction and is connected by an arm 12 to a rod 13 which intermediate its length is connected by a bell-crank lever 5^c with the stem of the valve in casing 5^a and to a bell-crank lever 10 2^c connected with the stem of the valve in casing 2^a; and by another arm 14 to a rod 15 which is connected by a bell-crank lever 4^d with the stem of the valve in casing 4^b. The bell-crank lever of the casings 5^a 2^a and 15 4^b are formed as illustrated so that when the trip 11^d is depressed by the carriage the valve in the casing 5^a will be opened to live steam and the valves in casings 2^a and 4^b will be closed to live steam. The trip 11^d is held in its normal raised position by a 20 spring 21^a and when so held the valve in casing 5^a is closed to live steam and the valves in casings 2^a and 4^b open to live steam. Another trip-lever crank shaft 16 is journaled in a suitable part of the frame near the limit of travel of the carriage in the other direction and is connected by an arm 17 to a rod 18 which intermediate its 25 length is connected to a bell-crank lever 2^d connected with the stem of valve in casing 2^b and also to a bell-crank lever 5^d connected with the stem of valve in casing 5^b. The trip shaft is also connected by another arm 19 to a rod 20 which is connected to a bell-crank lever 4^c connected with the stem of valve in casing 4^a. The bell-crank lever of the casings 2^b 5^b and 4^a are formed as 30 illustrated so that when the trip 16^d is depressed by the carriage the valve in the casing 5^b will be opened to live steam through the by-pass pipe 10^b while the valves in casings 2^b and 4^a will be closed to live steam. The trip 16^d is held normally raised by a 35 spring 21 and when in that position the casing 5^b is closed to live steam and the casings 2^b and 4^a open to live steam and closed to exhaust. Thus it will be observed that the 40 corresponding valves at the two ends of the piston cylinder and actuated by the two trips have the same operation under the 45 same conditions.

In the drawings the carriage is represented as having traveled to the right to the point where the hinged bracket 27 attached 55 to it has contacted with the trip 16^d and depressed it so that the valve in the casing 5^b has opened to live steam and the valves in the casings 2^b and 4^a have closed to live steam. The bracket 17 is suitably hinged, 60 say to the under side of the running board, as illustrated in Figs. 1 and 2 of the drawing, for instance by bolts or pins as shown, and has connected to it a rod or lever 28 by which it may be raised out of operative position if it be desired to run the carriage to 65

either end of the track without having the bracket actuate the trip.

In operation under normal conditions and assuming that the carriage is traveling from left to right, the sawyer's valve in casing 3^a as well as valve in casing 4^a are open to live steam and closed to their respective exhausts and the valve in casing 2^a is open to live steam while the sawyer's valve in the casing 3^b is closed to live steam and open to exhaust and the valve in casing 2^b is in open communication with casings 1^b and 3^b. Under these conditions the live steam passes from the supply pipe through casings 4^a 3^a 2^a and 1^a into the piston cylinder 3 through pipe or port 11^a and acting on the piston drives it and also the carriage to the right, and the steam in the cylinder forward of the piston exhausts through pipe or port into and through the casings 1^b 2^b and 3^b and from the casing 3^b through its exhaust port 7^b into the main exhaust port 8^b. If the sawyer now reverses his valves, live steam will be admitted to the right hand end of the cylinder from the live steam pipe or port 9^b and through the valve 1^b and pipe or port 12^b, and the steam in the other part of the cylinder will exhaust through pipe or port 12^a and casings 1^a 2^a and 3^a and the exhaust port 6^a of casing 3^a to the main exhaust pipe 8^a or atmosphere; and this operation will be repeated in alternation. On the other hand should the sawyer fail to do his duty, or his valves for any reason fail to promptly act, then in such case (assuming the carriage is traveling from left to right) when the carriage reaches the point of location of the safety trip it will contact with and depress the trip which will throw the arms 17 and 19 and rods 18 and 20 so as to close the valve in casing 4^a thus cutting off the supply of live steam to the pressure side of the piston cylinder and at the same time close the valve in casing 2^b and cut off the exhaust so that the steam in that end of the cylinder will cushion the piston. At the same time the valve in casing 5^b will be opened for the passage of live steam by way of the by-pass 10^b, branch pipe 11^b and casing 1^b and pipe or port 12^b into the cylinder so as to exert its pressure on the piston to drive the carriage in the other direction, the steam at the opposite side of the piston exhausting through pipe 12^a and casings 1^a 2^a 3^a into casing 4^a and out through the exhaust pipe or port 7^a of that casing. In the manner specified the travel of the carriage is automatically cushioned and checked and then reversed in its travel so that no injury can occur to any part of the apparatus. The travel of the carriage in the reverse direction will continue until the carriage leaves contact with the trip 16^d when the latter will be lifted to its former position by the spring 21 and the 130

affected valves restored to their normal positions and steam will be admitted and exhausted as before the valves were automatically operated, and if the carriage be moved 5 far enough to again strike the trip the same automatic checking and reversal will occur; and more or less recurrences of this alternate partial supply and partial exhausting of steam to and from opposite sides of the 10 piston will result in a practical counterbalancing of steam pressure on both sides of the piston and thus bring the carriage to a state of rest. This cushioning of the piston followed up by supply of live steam through 15 the by-pass will allow the carriage to be started gradually on its return travel instead of being started with greater impetus incident to admitting full pressure through the sawyer's valve without a preliminary cushioning and reversal effected as described. 20

In the travel of the carriage from right to left under normal conditions, whenever the carriage strikes the left-hand positioned trip 11^a that trip will be depressed and 25 the arms 12 and 14 moved so as to actuate the rods 13 and 15 to open valve in casing 5^a and close the valves in casings 2^a and 4^b so that the operation will be like that described for the parts in travel of the carriage from left to right. 30

In the manner described I provide a comparatively simple and compact arrangement of parts accurate and efficient for the purposes described and insuring an automatic 35 control of the carriage in its travel back and forth so that injury to the mechanism and to the operators is guarded against and prevented.

I have described particularly the preferred arrangement of the several parts but the same may be varied and essential features of the invention retained.

Having described my invention and set forth its merits what I claim is:—

45 1. The combination with a carriage, a cylinder, a piston therein and rod connecting it with the carriage, of a valve mechanism for controlling the supply of pressure fluid to the cylinder, another valve mechanism intermediate of the first mentioned valve mechanism and piston cylinder for closing communication between the cylinder and first mentioned valve mechanism, a third valve mechanism for admission of fluid 50 pressure to the cylinder when the second valve mechanism cuts off the supply of fluid pressure, and conduits for the pressure fluid in which the valve mechanisms are contained, substantially as described.

60 2. The combination with a carriage, a cylinder, a piston therein and rod connecting it with the carriage, of valve mechanism intermediate of the source of pressure fluid supply and said cylinder for controlling 65 the pressure fluid supply and comprising

an exhaust port and valve for controlling said port and passage of the fluid pressure, a second valve mechanism between the first mentioned valve mechanism and said cylinder for controlling the supply of pressure fluid to the cylinder and comprising an exhaust port and valve for controlling said port and in communication with said first mentioned valve mechanism and the cylinder, said valve mechanisms operating to permit passage of pressure fluid to the cylinder when both are closed to their exhausts and to permit exhaust of fluid from the cylinder through the exhaust of one valve mechanism when the exhaust is open and the exhaust of the other valve mechanism is closed, and conduits for the pressure fluid in which the valve mechanisms are contained, substantially as described. 70

3. The combination with a carriage, a cylinder, a piston therein and rod connecting it with the carriage, of valve mechanisms operatively connected together for manual operation to supply pressure fluid to one side of the cylinder piston and permit exhaust of fluid from the opposite side of the piston, in alternation, valve mechanisms for cutting off supply of pressure fluid to the manually operated valve mechanisms, valve mechanisms for cutting off exhaust fluid from the cylinder to the manually operated valve mechanisms, and valve mechanisms located in by-passes for the supply of pressure fluid to the cylinder, said valve mechanisms being operatively connected with the valve mechanisms which cut off exhaust from the cylinder to the manually operated valve mechanisms and operative therewith to cut off exhaust from the end of the cylinder when pressure fluid is supplied to that end of the cylinder by way of the valve controlled by-pass, substantially as described. 90

4. The combination with a carriage, a cylinder, a piston therein and rod connecting it with the carriage, of valve mechanisms operatively connected together for manual operation to supply pressure fluid to one side of the cylinder piston and permit exhaust of fluid from the opposite side of the piston, in alternation, valve mechanisms for cutting off supply of pressure fluid to the manually operated valve mechanisms, valve mechanisms for cutting off exhaust fluid from the cylinder to the manually operated valve mechanisms, valve mechanisms located in by-passes for the supply of pressure fluid to the cylinder, said valve mechanisms being operatively connected with the valve mechanisms which cut off exhaust from the cylinder to the manually operated valve mechanisms and operative therewith to cut off exhaust from the end of the cylinder when pressure fluid is supplied to that end of the cylinder by way 100 110 120 125 130

of the valve controlled by-pass, and mechanism operatively connecting one of the valve mechanisms which cut off supply pressure fluid to the manually operated valve mechanism in one of the by-passes and adjacent valve mechanism which cuts off exhaust from the cylinder whereby said valve mechanisms will cooperate to cut off supply pressure fluid to one end of the cylinder while pressure fluid is admitted to the other end through the by-pass and exhaust from the same end is cut off, substantially as described.

5. The combination with a carriage, a cylinder, a piston therein and a rod connecting it with the carriage, of a fluid pressure conduit and a by-pass therefrom provided for each end of the piston cylinder, manually operated valves provided for each conduit and connected one to the other for controlling the supply of pressure fluid to and exhaust from the cylinder at opposite sides of the piston in alternation, separately operative valves in the supply pressure fluid conduit of each end of the cylinder, connected valves positioned one in the by-pass and the other in adjacent supply pressure fluid conduit of each end of the cylinder, and trip mechanism connecting the separately operated valve in the supply

pressure fluid conduit at one end of the cylinder with the connected valves of the by-pass and supply pressure conduit at the other end of the cylinder, substantially as described.

35 6. The combination with a reciprocating member, a cylinder, a piston therein and a rod connecting it with the reciprocating member, of a conduit for supplying pressure fluid to the cylinder, a by-pass leading from said conduit and to the cylinder, a valve in the by-pass and another in the conduit, operatively connected one with the other so that as one opens the other closes, a valve including an exhaust in the conduit 40 for controlling the supply and exhaust of fluid to the cylinder under normal conditions, and an emergency valve including an exhaust in the conduit adapted to operate in an emergency to cut off the supply of 45 pressure fluid to the normal supply and exhaust valve and permit exhaust from the cylinder, substantially as described.

50 In testimony whereof I affix my signature in presence of two witnesses.

CHARLES FOSTER ASHLEY.
